UNITED STATES PATENT OFFICE.

BENJAMIN H. JEFFERSON AND ROBERT H. WAUD, OF CHICAGO, ILLINOIS, ASSIGNEES,
BY MESNE ASSIGNMENTS, TO LYON & HEALY, INC., OF CHICAGO, ILLINOIS, A COR-
PORATION OF ILLINOIS.

MUSICAL INSTRUMENT AND LIGHTING SYSTEM THEREFOR.

Refiled for application Serial No. 266,858, filed December 16, 1918. This application filed March 23, 1921,
Serial No. 454,748.

To all whom it may concern:

Be it known that we, BENJAMIN H. JEFFERSON and ROBERT H. WAUD, citizens of the United States, residing at Chicago, in the county of Cook and State of Illinois, have invented a certain new and useful Improvement in Musical Instruments and Lighting Systems Therefor, of which the following is a full, clear, concise, and exact 10 description, reference being had to the accompanying drawings, forming a part of this specification.

Our invention relates to musical instruments and lighting systems therefor, and 15 particularly to pianos and illuminating means associated therewith.

This application is refiled for application Serial No. 266,858 filed December 16, 1918.

20 The primary aim of the present invention is to provide an improved system of lighting a piano and the room or place containing it, and more particularly to afford a more efficient directing of light for 25 illuminating the music rack and keyboard thereof. In keeping with this we provide a novel and improved arrangement of circuits and disposition of lamps and flexible conductors therefor, so that the music rack 30 and keyboard may be illuminated from both sides.

Further aims of our invention are: first, to arrange for the effective use of the lighting system with the piano either open or 35 closed, in which latter case the system will be useful in beautifully and artistically lighting the room or place containing the piano; second, to permit the easy and quick opening and closing of the piano without 40 interfering with or interference by the lighting system; third, to permit the ready connection and disconnection of the piano lighting system with the wiring system of rooms, hallways and the like; fourth, to permit this connection at the most convenient 45 point in the piano; and fifth, to afford means for connecting other lighting devices, such as a floor or table lamp, with the piano.

In the accompanying drawings Fig. 1 is 50 a plan view of a grand piano provided with a lighting system embodying our invention;

Fig. 2 is a vertical section taken on line 2—2 in Fig. 1, but on an enlarged scale;

Fig. 3 is a detail sectional view taken on line 3—3 of Fig. 1, also on an enlarged scale.

Referring to the drawings, we show a grand piano A, provided with a lighting system embodying our invention. It will be understood, of course, that in its general features our improved lighting system may be applied to other types or styles of pianos.

In the arrangement shown for carrying out the invention we provide two lamps 1 and 2 which are adapted to be used at the opposite ends of the piano keyboard. As shown in the drawings they are placed upon the hinged portion 3 of the cover 4. This cover 4 is the usual cover or lid of a grand piano and is hinged at its edge 5 so that its opposite edge 6 may be lifted and the cover as a whole swung back into a tilted position to permit the sound to better escape from the piano. In the drawings this cover or lid 4 is shown in a closed position and the hinged end 3 also in a closed position and the lamps 1 and 2 resting upon the latter.

When the piano is to be opened the lamps 1 and 2 are lifted from the member 3 and moved back toward the rear of the piano. They are rested upon the piano top or cover 4, well to the rear, and then the member 3 is swung upwardly, backwardly and downwardly so as to rest on cover 4 and open the piano. Then the lamps 1 and 2 are placed on the shelf 7 at opposite ends of the keyboard. Thus the keyboard is well lighted, by lights at each end, as is also the music on the music rack. This lighting effect is not interfered with by the body, head or hands of the player.

The lamps 1 and 2 may be of any one of a large variety of constructions. We show a very artistic type of lamp having a small base 8 preferably made of wood and an incandescent lamp surrounded by a shade 9.

The lamps 1 and 2 are supplied with insulated wire cords or connections 10 and 11, respectively. The cord 10 is extended to a plug 12 and the cord 11 to a plug 13. The plugs 12 and 13 fit into sockets 14 and 15,

respectively. The cords or flexible conductors 10 and 11 are of sufficient length and are connected at such points as to permit movement of the lamps to the side 5 and rear sufficiently to allow section 3 to clear them when said section is swung back to open the piano. The cords or connectors 10 and 11 also permit movement of the lamps back onto section 3, when same is 10 closed, and from place to place on top of same to a limited extent to secure room lighting effects.

When section 3 is closed spaces 11'-11" are afforded between the underside of said 15 section and the top margins of the side portions 12'-12", by means of rubber tips 13', secured to the section 3, thus permitting passage and movement of the conductors 10 and 11.

20 The sockets 14 and 15 are preferably mounted on the inner face of the piano casting 16. From the socket 14 conductors 17 and 18 extend to another socket 19 which is conveniently mounted on a cross beam 20 of 25 the piano frame. From the sockets 19 other conductors 21 and 22 extend to still another socket 23 which is conveniently mounted on another cross beam 24. This last mentioned socket 23 is connected with still another socket 25 by means of conductors 26 and 27, said socket 25 also preferably being mounted on the beam 24. This last mentioned socket 25 is connected with the socket 15 by conductors 28 and 29.

35 Thus it will be seen that the lamps 1 and 2 are connected with the adjacent sockets 14 and 15. It will also be seen that these sockets 14 and 15 are connected with a wiring system comprising three other sockets 19, 23 and 25, and that connections of various kinds may be made with any one or more of these three last mentioned sockets. For example, we show a connection by main feed conductors 30 and 31 with the socket 40 23. This connection is intended to indicate an outside connection with a source of electrical energy, such for example, as an ordinary house or hall lighting system, whereby the piano lighting system will be supplied 45 with electrical energy for lighting the lamps 1 and 2. If more convenient or desirable the outside connection may be made with either of the sockets 19 or 25, instead of with the socket 23. Assuming however, that 50 the outside connection is made with the socket 23, as shown, the sockets 19 and 25 may be idle, or either or both of them may be connected with some outside lighting device in order to supply electrical energy to the 55 same. For example, we show a connection consisting of conductors 32 and 33 extended from the socket 19. These conductors 32 and 33 may run to a separate lamp, as for example, a floor or table piano lamp which 60 thus may be conveniently supplied from a

connection with the piano lighting system. Thus the lighting system provides not only a practical and very advantageous arrangement for lighting the piano, its keyboard and music, but furthermore, the system is 70 highly flexible, permitting various kinds of connections to be made to supply it with electrical energy and also permitting outside connections to be made so as to energize other adjacent lighting or electrical devices 75 if wished. For instance, connections can be made for a vacuum cleaner or electrically operated Victrola or reproducing piano or other device.

We desire to particularly emphasize the 80 arrangement of the flexible conductors and lamps, whereby the latter may be moved from place to place on the piano, and whereby the cords do not interfere with the facile movement of the cover section 3.

85 It will also be noted that the lamps are not disconnected nor their circuits or connections in any way interfered with when the piano cover is closed down, and that therefore they will be fully effective in lighting the room or place containing the piano, thereby utilizing the piano lighting system for room lighting as well as piano lighting in place of other wall or floor lamps.

90 It will be understood that changes and 95 modifications may be made without departing from the spirit of the invention.

What we claim is:

1. The combination with a musical instrument comprising a sound box mounted on 100 suitable supports, and having a cover provided with a front hinged section, a sliding shelf under said hinged section, said section and the top portions of the side walls being spaced to provide openings, of a main feed 105 circuit having two branches terminating adjacent the inner forward ends of said side walls, separable connectors forming the terminals of said branches, and mounted on the inner faces of said side walls, lighting devices on said hinged front section and flexible conductors passing through said openings to connect said lighting devices and separable flexible connectors when the section is closed, said conductors being of sufficient length to permit removal of the lighting devices from the instrument without disconnection to permit said section to be raised. 110 115

2. The combination with a musical instrument including a body having side walls, 120 a front shelf on said side walls, a hinged cover on said body provided with a hinged front section adapted to close over said shelf, of means for maintaining said front section in spaced relation to the upper margins of 125 said side walls when closed, portable lighting devices adapted to stand on said front section and on said shelf when the front section is open, detachable conductors entering said body, a separable connector therein, 130

branches extending from said connector and permanently arranged in said body, said conductors terminating inside the body under said front cover section, separable ¹⁰ 5 connectors forming the terminals of said branch conductors, and flexible conductors connecting said lighting devices and said terminal connectors and adapted to extend through said spaces between the cover section and said side walls.

In witness whereof, we hereunto subscribe our names this 18th day of March, A. D. 1921.

BENJAMIN H. JEFFERSON.
ROBERT H. WAUD.
